UNITED STATES PATENT OFFICE.

ELMER A. GRIFFITS, OF CALGARY, ALBERTA, CANADA.

COMBINATION MOUNTING FOR MOTORS AND FITTINGS.

Application filed March 3, 1923. Serial No. 622,703.

To all whom it may concern:

Be it known that I, ELMER A. GRIFFITS, a citizen of the United States, and a resident of the city of Calgary, in the Province of Alberta and the Dominion of Canada, having invented certain new and useful Improvements in Combination Mountings for Motors and Fittings, do hereby declare the following to be a full, clear, and exact description of the same.

My invention relates to improvements in a combination mounting for motors and fittings which is enclosed in a cabinet when not required for use and to which a multiplicity of fittings such as an egg beater, a meat grinder, or other objects may be attached, the mounting being in such a form that variations of speed for the attachments may be obtained without reducing the speed of the driving motor.

The cabinet feature is a means for saving floor space with the device at hand at all times. The position of the accessories relative to a table beneath may be changed as desired to suit articles used in connection therewith, provision being made for raising and lowering the mounting carrying the accessories upon guides within the cabinet.

It will be readily understood that a device of this kind is an accessory for the culinary department and is particularly adapted for use where floor space is limited and a utility device needed.

The drawings are illustrative of the device only so far as its adaptability is concerned in which—

Fig. 1 is a vertical elevation with one side of the cabinet removed and shows a meat grinder attached ready for operation in relation to a pan upon a table.

Fig. 2 is a plan view with the top of the cabinet removed.

Fig. 3 is a vertical elevation with one side removed and the mounting in the vertical position within the cabinet.

Fig. 4 is a front elevation with the door open showing the device in the vertical position within the cabinet. This view also shows the lugs upon the lower side of the base plate to which the utensils are secured.

Fig. 5 is a cross section through on the line B. B., Fig. 2 showing the method of attaching the utensils.

Fig. 6 is a section of the line A. A. Fig. 5 showing the pawl to secure the mounting

at the desired height in relation to the cabinet.

Fig. 7 is a section through the handle and a fragment of the mounting plate showing the cables to release the pawls of the raising and lowering device.

Similar characters refer to similar parts throughout the several views:

The device has a substantially flat mounting plate 7, at one end of which on each side are turned up flanges 8. These flanges are pivoted as shown at 21 to bracket members 9, one on each side. The brackets 9, have rollers 10 mounted thereon, the peripheries of which rollers are grooved and adapted through their mountings to traverse the rods 3 as hereinafter described and to stiffen this bracket and retain the rollers in correct relationship to one another plates 6 are mounted parallel to the plates 9. The rollers 10 are mounted in pairs between the said plates 6 and 9 and between the peripheries of the said pairs of rollers is a rod 3. Similar rods 3 are mounted in relation to each set of rollers 10, forming parallel perpendicular guides which are secured in the base and top of a cabinet 1, and adjacent the sides thereof. The position of the brackets 9 may be raised or lowered upon the rods 3 and to retain the brackets in the desired position dogs 5, are pivoted upon the bracket 9 which engage in horizontal grooves 4 formed in the rods 3. To facilitate the raising and lowering a balance weight 11 is provided, with cables 12, passing over pulleys 13 mounted in the top of the cabinet and connected to the brackets 9. To release the dogs 5 from engagement with the rods 3, cranks 14 are provided which are pivoted upon the plate 7 to which cranks cables 15 are connected. Guide blocks 16 are mounted upon the said plate 7 through which the cables 15 pass and between which and the crank coil springs 17 are placed. The cables 15 after passing along the sides of the plate 7 are connected to an equalizer 18, which equalizer is in turn fastened by a cable 20 to the tubular handle 19 at the end of the plate 7. The interior surface of the handle 19 is uneven forming a cam surface which corresponds with a surface formed upon the tubular end of the plate 7. Thus one half a revolution of the handle will exert a pull upon the cables 15 and release the dogs 5. It will be seen that the

mounting plate 7 is pivoted to the brackets 9 through the flanges 8, and may be swung from the perpendicular position in which it is enclosed within the cabinet 1, to the horizontal position and to retain the plate in the horizontal position a quadrant 22 is formed upon the bracket 9 which is engaged by a dog 23 pivoted upon the flange 8 of the mounting plate 7. Upon this 10 mounting plate 7 a driving motor 24 is mounted. This driving motor has a toothed pinion 25 mounted within the mounting plate 7, which meshes into a train of gearing mounted upon the said plate 7. One of these gears 26 will give slow speed and another 27 will give medium speed.

The hubs of these gears are each bushed into the mounting plate upon the upper side and extend through the mounting plate 20 on the lower side, as shown in detail in Fig. 5. In the centre of the hubs of these gears upon the lower side rectangular holes are provided which holes 28 are for the reception of drive shafts for accessories. The accessories are demountable from the plate 7 and the gears and are provided with shafts to fit into the rectangular holes 28, segmental lugs 29 are provided upon the underside of the said plate 7 to hold accessory 25 mountings 30 one set of lugs being provided for each different gear. A shaft 31 with a square end fitting into the rectangular holes 28 delivers the power from the gear wheels to the fitting and by connecting up to the 35 gear 25 power is taken direct from the motor at high speed. Connecting to gear 26 gives low speed and greater power and connecting to gear 27 gives medium speed. The

mounting 30 forms a bearing for the shaft 31 outside of the mounting plate 7 giving 40 greater stability and the lugs 29, of gear 26 are of larger radius to the others to fit a meat grinder or any other device of a similar character where power and slow speed are necessary.

What I do claim as my invention, and desire to secure by Letters Patent is:—

1. An article of the class described comprising a driving motor and a train of gears driven thereby, a base plate mounting for the said motor, means for holding accessories upon the said base plate in relation to and driven by any member of the gear train, brackets upon which the said base plate is pivoted, supporting rods upon which the brackets are movable and a cabinet interiorly of which the said rods are mounted.

2. An article of the class described comprising a driving motor and train of gears driven thereby, a base plate mounting for the motor and for holding accessories thereon in relation to and driven by the members of the gear train, with brackets pivoted upon the sides of the said base plate adjacent one end thereof the said brackets consisting of parallel plates with rollers therebetween with supporting rods which the said brackets traverse, securing members to hold the said brackets in relation to the supporting rods and a cabinet adapted to enclose the whole of the supporting rods and apparatus carried thereby.

ELMER A. GRIFFITTS.
